REFRIGERATED FOOD LOCKER ROOM

George B. Quatman, Lima, Ohio

Application December 22, 1943, Serial No. 515,202

6 Claims. (Cl. 62—102)

This invention relates to food locker rooms of the type in which banks of lockers for meats, fruits, vegetables and the like are arranged within the room where it is desired to keep the temperature of the food relatively low so that it may be stored for a substantial period of time.

Heretofore food locker rooms are so refrigerated that customers entering the room to gain access to their lockers, must withstand the very cold temperature at which the room is maintained. It will be understood that in most of these rooms, the entire area is refrigerated and the cold is so intense that the customers can remain but a very short time within the room. This is not only costly but a waste of energy. Refrigerating coils are used for cooling these locker rooms and it is necessary that the coils be cleaned of the frost by hand which is a most uncomfortable work due to the extreme cold which must be maintained at all times.

Some locker rooms have been constructed so that the room that the customer enters has a normal temperature but the bank of lockers must be brought to the customer from some cold storage space by means of mechanically operated equipment which is difficult and burdensome for the inexperienced to operate. This necessitates bringing the entire bank of lockers into a space with high humidity, resulting in a condensation of this humidity in frost and ice on the lockers, the door openings, locks and the food itself.

It is a desideratum to provide a food locker room in which the lockers per se are properly refrigerated, but in which the room itself can be kept at a temperature sufficiently comfortable to enable customers to remain therein as long as is necessary, thereby not only contributing to the comfort of the customer but also reducing the area which is required to be refrigerated, and eliminating any mechanical conveying devices to permit the customer to gain access to his locker and preventing any other lockers than the one the customer wishes to gain access to from being exposed to higher temperatures and higher humidity.

An object is to produce a locker room in which the series of lockers are refrigerated in such manner that the individual locker is exposed to the cooling influence of circulating air on a plurality of sides, one side having a door accessible from an unrefrigerated room, thereby contributing to the comfort of customers, reducing the area necessary for refrigeration and eliminating the difficulty heretofore experienced

in cleaning refrigerating coils ordinarily employed for refrigerating food lockers.

Other objects and advantages of the invention will hereinafter appear and for purposes of illustration but not of limitation, an embodiment of the invention is shown on the accompanying drawings in which

Figure 1 is a vertical sectional elevation of a portion of a food locker room showing the banks of lockers in position;

Figure 2 is an enlarged transverse sectional view of the room showing details of construction; and

Figure 3 is a diagrammatic view of a food locker room in accordance with the invention.

The illustrated embodiment of the invention comprises a room R of any suitable dimension. Arranged within the room may be any desired number of food locker banks B having any desired number of food lockers arranged in vertical piles or banks which are spaced from the next adjacent pile and arranged in a manner hereinafter to be described. Since the construction of the individual rows of lockers will be the same in each instance, description and illustration of one is deemed sufficient.

As indicated in Figure 1, it will be understood that the bank of lockers B is mounted on a floor having subjacent heat insulating material F such as cork. The sides and back S also are provided with heat insulating material and above the ceiling is likewise heat insulating material C. Any desired heat insulating material well-known to those skilled in this art, may be employed for this purpose.

As shown on Figure 1, there are three piles of lockers indicated at 1, 2 and 3. The individual lockers 10 in these piles constitute in this instance, a compartment which may be of metal or other heat conducting material closed on all sides except for the front which has a hinged door 11 of construction to provide satisfactory and efficient insulation and sealing, the same being indicated on Figure 2. The doors 11 are accessible outside of the insulated area and free from the extreme cold.

Above the various banks of lockers is an air duct 12 and a duct 13 is provided adjacent the locker most remote from the source of refrigerated air as will hereinafter appear. The lowermost locker of each pile is spaced from a horizontal wall 14 to form an air duct 15. The wall 14 is a continuous one running from the pile nearest the source of cold air to the most remote pile 3 where it terminates in spaced rela-

tion to the adjacent side wall to enable the air to be drawn back to the refrigerating unit through a duct 16. It will be understood that each pile of lockers is spaced from the next adjacent pile to provide vertical air ducts 18.

From the above description, it will be understood that air from a refrigerated source is forced by means of a blower B into the duct 12 and then passes through the ducts above mentioned around three or more sides of each of the food lockers 10. The front or access door 11 of each locker is not subjected to the cold air. After the cold air has completely passed around all of the lockers, it is returned to the refrigerating machine M through the return duct 16. Detail description and illustration of the refrigerating machine M and the blower system B is not given because it will be readily understood by those skilled in this art. Suffice it to say that the flow of cold air at the desired temperature is maintained continuous and in a substantially closed circuit and the cold air is employed only to refrigerate the lockers without refrigerating the aisles between the banks of lockers. In this manner the cost of refrigeration is substantially reduced as well as affording greater comfort to the customers using the lockers.

It is desirable that the cold air entering the locker compartment travel at a relatively slow speed in order to afford the best element of time in which to absorb temperature from the food lockers and after the cold air has traveled its course among all of the lockers and thus absorbed its heat to return it at as rapid speed as practical from the locker space. For this reason, air duct 12 through which the cold air enters is constructed proportionately larger than air duct 16 through which the air returns to the source of cold air supply.

It will be manifest that the banks of lockers may extend a considerable distance because, as above mentioned, the number of locker piles such as 1, 2 and 3, may be considerable as, for example, to extend from one end of the locker room to the other. As a consequence, those piles closest to the source of refrigerated air will come in contact with the coldest air, whereas those at the extreme end remote from the refrigerating source will be exposed to air whose temperature is somewhat increased. It is, therefore, desirable that the more remote the piles are from the refrigerating source, the more the air should be deflected or baffled about the individual locker units. With this in view, a series of fins or baffles 20 are disposed at the top of each locker pile in the region of the vertically disposed ducts 18. These baffles which are rearwardly curved, that is, curved rearwardly of the direction of the cold air stream, deflect the air in the desired direction.

It will be noted in Figure 1 that there are three baffles or fins shown 20, 20a and 20b, and also that the baffle 20a is somewhat longer than the baffle 20 and the baffle 20b is somewhat longer than the baffle 20a. In other words, the more remote the pile is from the refrigerating source, the longer will be the baffles, thereby to deflect a greater volume of cold air to those lockers more remote from the refrigerating source. The farther the lockers are from the refrigerating source, the more deflection of the air stream is effected. The opening in the air duct 12 through which the air passes to passage 18 is also smaller at the first opening, increasing in size with each succeeding opening to the largest opening at the

most remote stack of lockers, such as at 3, thus affording a control for a uniform quantity of air at each group of lockers due to any pressure differential that may occur at the first group of lockers over the air pressure at the most remote group of lockers, or increased quantity to offset decreased temperature as desired. Thus, although the air at the lockers most remote from the refrigerating source may be at a somewhat lower temperature, or lower pressure, nevertheless by baffling or deflecting the air stream, a greater volume of air and uniform cold distribution may be brought into direct contact with the several sides of these lockers, thereby to maintain them at the desired temperature. It must also be noted that the only means of the circulated air to return to the source of supply is through duct 16 which opens to the refrigerated chamber only in the corner of the locker chamber remote from the blower B thereby creating a partial vacuum at that point. Thus the entire quantity of air induced into the chamber must pass all locker stacks to absorb the heat before it can be returned to the source for recooling.

From the above it will be readily apparent that the cold air does not at any time come into contact with the contents of the locker thereby militating against dehumidification of the food within the locker.

It is to be understood that numerous changes in details of construction, arrangement and operation may be effected without departing from the spirit of the invention especially as defined in the appended claims.

What I claim is:

1. A food locker comprising an enclosed room, a compartment within and forming a part of said room and insulated therefrom, a plurality of banks of food lockers within said compartment spaced from each other, the lockers of each bank opening directly into the room through said front, an insulated door individual to each locker for closing the front thereof and the same being accessible from within said room thereby to enable a patron to gain access to a locker from the room and without being subjected to the temperature of the compartment, means for introducing cooled air at one end of said compartment, and a return duct for withdrawing air from said compartment, said return duct being disposed at the bottom end of the compartment beneath said banks and communicating with the inside thereof at a remote point from said air inlet.

2. A food locker comprising an enclosed room, a compartment within and forming a part of said room and insulated therefrom, a plurality of banks of food lockers within said compartment spaced from each other, the lockers of each bank opening directly into the room through said front, an insulated door individual to each locker for closing the front thereof and the same being accessible from within said room thereby to enable a patron to gain access to a locker from the room and without being subjected to the temperature of the compartment, and means providing a closed air system including means to introduce cold air to one end of the compartment and to withdraw air therefrom at the same end, the latter having a return duct communicating with the remote end of the compartment.

3. A food locker comprising an enclosed room, a compartment within and forming a part of said room and insulated therefrom, a plurality of banks of food lockers within said compartment spaced from each other, the lockers of each

bank opening directly into the room through said front, an insulated door individual to each locker for closing the front thereof and the same being accessible from within said room thereby to enable a patron to gain access to a locker from the room and without being subjected to the temperature of the compartment, means for introducing cold air under pressure through one end wall of said compartment, means for causing circulation of a greater volume of air around those banks more remote from said last end wall in such manner that the more remote the bank is spaced from said last end wall, the greater volume of air is circulated about the respective bank, and a return duct leading from the region of the remote end of said compartment and extending therefrom through said last end wall.

4. Food locker as claimed in claim 3 comprising deflectors for each locker bank for deflecting or baffling air to the respective bank, the deflectors increasing in area as the banks become more remotely spaced from said last end wall so that the more remote the locker bank is from said last end wall, the greater will be the volume of air circulated about the same.

5. Food locker comprising a room, a compartment within the room, said compartment having top, bottom, back and end walls, insulation sealing the top, back and end walls of said compartment, a plurality of vertical banks of food lockers within said compartment, each bank being spaced from the top and bottom walls of said compartment to provide top and bottom air ducts, means sealing the bottom air duct from said banks to provide a return air duct beneath same, there being an opening at one end of said compartment for communication with said return air duct and the space between an end

bank and the adjacent side wall of the compartment, said banks being spaced laterally from each other with the front thereof open to said room, insulated door means providing a direct closure for the lockers of said banks and being accessible from said room, and means for introducing under pressure refrigerated air into the air duct at the top of said banks and for withdrawing air from said return duct.

6. Food locker comprising a room, a compartment within the room, said compartment having top, bottom, back and end walls, insulation sealing the top, back and end walls of said compartment, a plurality of vertical banks of food lockers within said compartment, each bank being spaced from the top and bottom walls of said compartment to provide top and bottom air ducts, means sealing the bottom air duct from said banks to provide a return air duct beneath same, there being an opening at one end of said compartment for communication with said return air duct and the space between an end bank and the adjacent side wall of the compartment, said banks being spaced laterally from each other with the front thereof open to said room, insulated door means providing a direct closure for the lockers of said banks and being accessible from said room, means for introducing under pressure refrigerated air into the air duct at the top of said banks and for withdrawing air from said return duct, and fins for deflecting air at the top of each bank causing the air to pass downwardly along the sides thereof, the fins for the individual banks gradually increasing in area from the inlet end of the compartment to the outlet end thereof.

GEORGE B. QUATMAN.
